(57) CLAIM

The ornamental design for a personality pillow, as shown and described.

DESCRIPTION

FIG. 1 is a left view showing my new design for a personality pillow;

FIG. 2 is a front view thereof;

FIG. 3 is a right view thereof; and,

FIG. 4 is a back view thereof.

The broken lines shown in the drawings are included for the purpose of illustrating environmental structure and form no part of the claimed design.
